PORATION OF GREAT BRITAIN.

RECEIVING SYSTEM FOR ELECTRIC WAVES OR CURRENTS OF CONSTANT FREQUENCY.

Application filed June 1, 1922, Serial No. 565,070, and in France June 9, 1921.

This invention relates to a receiving system for electromagnetic waves or electric currents of constant frequency, and of a selective and anti-parasitic nature.

5 It essentially comprises, among other elements or parts, one or more amplifying circuits of a sufficiently aperiodic character comprising three-electrode audions or vacuum tubes or like devices, said circuits affording the following results:

1. The electromagnetic waves are amplified (after amplification and detection):

a. By superposing thereupon sustained oscillations such that their frequency shall 15 be equal to that of the detected waves or sub-multiples of this frequency (so that the said sustained oscillations shall be harmonics of the detected waves) or a multiple of said frequency (so that the detected waves shall

20 be harmonics of the sustained oscillations). The superposition of these two waves will give rise to a resulting amplified wave whose period is equal to or different from the period of the detected waves, the two periods, old or new, remaining however in a simple ratio.

b. By amplifying this resulting wave by means of a series of resonant amplifying circuits which are tuned to the length of said 30 resulting wave.

2. Limitation is made in two or more of the amplification stages of the amplitude of the resulting wave by the saturation obtained by limiting the heating of the amplifying 35 audions, or by like means for limitation of amplitude.

The selection and the anti-parasitic effect are afforded by the simultaneous action firstly of the amplification obtained by the 40 superposition, upon the detected waves, of sustained oscillations of the same frequency or a frequency which is a multiple or sub-multiple of the same, and secondly by the limitation of the amplitude of the current 45 by saturation or by like means.

The various steps involved in the present invention are as follows: After detection, sustained waves are superposed upon the signal waves and the parasitic waves. Since 50 the period of the sustained waves is a multiple or a sub-multiple of the signal waves to be received, the use of the present invention results in obtaining, as concerns the

received waves, resulting amplified waves of the same period (or of a different period) 55 as that of the signal waves. The effect of superposing the local sustained wave is, in addition to the amplifying effect, a differentiation of the resulting sustained waves to be received from the waves resulting from the 60 parasitic effects.

The resulting waves are then amplified by a suitable number of audions which are coupled together by practically aperiodic circuits. These circuits provide for amplification and at the same time prevent the parasitic wave due to a damped wave from causing these circuits to vibrate at their proper period, since such vibration would set up oscillations tending to bring them near the 70 sustained oscillations which it is desired to receive.

The oscillations are then transmitted to resonant amplifying circuits which are tuned to the length of the waves resulting from the superposition of the local wave upon the signal waves. In these circuits since the waves have already been sufficiently amplified by the superposition of the local waves and the aperiodic circuits, the saturation of the 80 audions may be limited by regulating the heating current of the filaments so that the waves resulting from the parasitic waves whatever the intensity of the latter, are not given a greater amplitude than that given to the signal waves. In this manner the waves resulting from the parasitic waves may be eliminated by the use of a sufficient number of resonant circuits, said parasitic waves being absorbed by the losses in the resonance 85 circuits not adapted for the periods of the parasitic waves, which periods are different from those of the received signal waves, which latter alone are amplified by said resonance circuits.

90 This may be obtained for example by the arrangement of circuits which is shown in the accompanying drawing, the same being disposed after the detection circuit of any suitable receiving system. The arrangement 100 of circuits as therein set forth represents simply the stages of an entire receiving system according to the present invention.

In the said diagram, *a* indicates the entering terminals of the detected waves of constant audible frequency accompanied by the 105

parasitic waves, *b* the terminals of the succeeding stage (amplifiers of the resonance type) not shown but which may be of any known or other suitable form containing *b* audions coupled through tuned circuits, *c* aperiodic transformers, *d* three-electrode audions, *g* the primary or storage battery for potential, *p* the heating storage battery, *r* the heating rheostat, *h* a heterodyne of low frequency, and *d* the induction coil of the latter.

The particularly important point in this arrangement of circuits is the regulation of the heating of the audions in order to limit *15* the amplitude of the current by the saturation of said audions.

In any event, the heating of the audions should be so regulated that on the one hand *20* the heating shall be sufficient to cause the sounds to remain audible with the different stages of transformation, and on the other hand the heating shall be sufficiently lowered in order to obtain a saturation of the requisite low degree and hence to eliminate *25* parasite effects.

The present invention, however, is concerned with the case in which the parasites have a greater amplitude than the signals (if they have a lesser amplitude, they are not *30* troublesome). In such a case the limitation affects the parasites only, and the extent of the limitation is governed by the intensity of the saturation current which in its turn, depends on the heating of the filament as is *35* well known, so that by regulating this heating the parasites may be cut down to practically the amplitude of the signal.

It is obvious that the hereinbefore *40* described devices are given solely by way of example and are not of a limitative nature, and that they are susceptible of modifications without departing from the principle of the invention. In particular, the said arrangement has been disposed on the heterodyne *45* system, but the same arrangement could be disposed on the autodyne system; on the other hand, the number of stages of amplification can be increased. In like manner, a single heating rheostat has been provided, but

use may be made of a rheostat for each audion, and like devices can be employed. *50*

What we claim is:

1. The method of operating upon electrical signal waves of constant audible frequency accompanied by parasitic waves of greater *55* amplitude and different frequencies after detection, which comprises superposing thereon sustained local waves of a frequency bearing a simple ratio to that of the signal waves, passing the resultant waves through a non-resonant amplifier, and passing the waves from said amplifier through a second amplifier tuned to the frequency of the waves resulting from the superposition of the local waves on the signal waves, while reducing *60* the ratio of amplification of waves above a given amplitude in proportion to the ratio of amplification of waves below said given amplitude to bring the amplitude of the amplified resultants of the parasitic wave *65* down to substantially the level of the amplified resultant of the signal waves.

2. The method of operating upon electrical signal waves of constant audible frequency accompanied by parasitic waves of *70* greater amplitude and different frequencies, after detection, which comprises superposing thereon sustained local waves of a frequency bearing a simple ratio to that of the signal waves, passing the resultant waves through amplifier circuits containing audions coupled through non-resonant *75* transformers, and passing the waves from said amplifier circuits through a second set of amplifying circuits containing audions and *80* tuned to the frequency of the waves resulting from the superposition of the local waves on the signal waves, while regulating the heating of the filaments of the audions to bring the amplitude of the amplified resultants of the parasitic waves down to substantially *85* the level of the amplified resultant of the signal waves.

In testimony whereof we have signed this specification.
